[57] CLAIM

The ornamental design for an automobile tire, as shown and described.

DESCRIPTION

FIG. 1 is a front elevational view of the automobile tire showing our design, it being understood that the tread pattern is repeated throughout the circumference of the tire;

FIG. 2 is a rear elevational view thereof;

FIG. 3 is a right side elevational view thereof;

FIG. 4 is a left side elevational view thereof;

FIG. 5 is an enlarged fragmentary front elevational view thereof; and

FIG. 6 is a sectional view taken along the line 6—6 of FIG. 5.

FIG. 1
